BAG WAXING MACHINE

Edwin F. Anderson, Buffalo, N. Y., assignor to
 Pillsbury Flour Mills Company, Minneapolis,
 Minn., a corporation of Delaware

Application April 22, 1943, Serial No. 484,091

9 Claims. (Cl. 91—46)

1

This invention relates to an apparatus for coating and sealing the filling ends of paper bags and other containers after the same have been filled and the filling ends stitched or otherwise secured.

At the present time multiple-wall paper bags are extensively used for packaging granular and pulverized materials and such bags as made by the manufacturer are collapsed flatwise and have the lower end thereof stitched, bonded or otherwise secured together to form a reinforced tab and such tab is further reinforced, coated and sealed by the manufacturer, usually with a heavy coating of wax. Such bags are tubular and are distended and filled with material from conventional dispensing and measuring machines whereafter the opposite sides of the filling end or upper end of the bag are collapsed together and secured to form an upper tab by stitching, bonding or other securing means. It is then necessary and required by Government regulations to seal and coat the upper tab so formed with a heavy coating of self-hardening material, such as wax or paraffin.

An object is the provision of simple, highly efficient apparatus which can be produced at relatively low cost and which is fully automatic and continuous in operation for successively coating a multiplicity of bags or other containers of the type described.

More specifically it is an object to provide bag coating or waxing apparatus of the type described which employs minimum number of working parts and which utilizes a pair of cooperating screw type conveyor elements in a dual capacity for both supporting a filled bag in inverted position for dipping the flattened filling extremity thereof in a trough containing melted wax or other coating ingredients and for also bodily moving the said bags longitudinally of the machine across the coating-containing trough and therebeyond to coat the tabs formed at the filling ends and to facilitate hardening of the coated tabs before the bags are discharged from the apparatus.

These and other objects and advantages of the invention will more fully appear from the following description made in connection with the accompanying drawings, wherein like reference characters refer to the same parts throughout the views and in which—

Fig. 1 is a plan view of an embodiment of my apparatus showing a filled bag about to be tilted into inverted position and so received by the supporting and conveying medium of my apparatus and showing several other bags in progress through my apparatus;

2

Fig. 2 is a side elevation of my said apparatus; Fig. 3 is a vertical section taken approximately on the line 3—3 of Fig. 2;

Fig. 4 is a vertical section taken on the line 4—4 of Fig. 2; and

Fig. 5 is a perspective view with some portions broken away and others shown in section of a multiple-wall paper bag filled with granular material and having its filling end coated and sealed by my improved apparatus.

The form of my apparatus illustrated includes an elongated upright frame, as shown, comprising two series of opposed spaced posts 6 which may conveniently be constructed from metal pipe having attachment pedestals 6a secured to the lower ends thereof for bolt or screw attachment to a horizontal supporting surface or floor. Opposed pairs of said posts 6 may be secured together and braced by transverse pipes or other suitable members 7.

At the upper portion of the elongated frame so constructed a pair of parallel spaced rotary shafts 8 are suitably journaled and extend throughout the length of the frame and have the right hand ends thereof journaled in suitable bearings 9 attached to the two respective right hand end posts 6 of the frame. The left hand ends of the rotary shaft 8 are journaled in similar bearings 10 mounted at the upper ends of

the respective left end posts of the frame. The axes of the two parallel shafts 8 are aligned in a plane inclined slightly from the horizontal from the right hand ends of their left hand extremities. Additional bearings 11 for the medial portions of

the elongated rotary shafts 8 are provided at the upper end of the intermediate posts 6. Shafts 8 are connected for driving in opposite directions and constitute a supporting medium for the bags which are to be processed, as well as a conveying

medium for moving the filled bags through the machine horizontally and longitudinally of the frame. To obtain such conveying function I provide the two shafts 8 with a helically wound conveying element 8a the convolutions thereof being rather widely spaced and the windings of the two shafts 8 being opposite to cooperate in progressing the bags. The double screw conveyor may be conveniently formed by securing, by welding or other suitable means, a helical coil 8a of

rod material to the external periphery of the shafts 8. The helical coils 8a are broken or interrupted at the medial portions of the respective shafts 8 to accommodate the central bearings 11.

Suitable driving means are provided for the

two rotary shafts and as shown comprise for each shaft a beveled gear 12 mounted on the inner end of a stub shaft 12a which is journaled in a suitable bearing 13 mounted on one of the left end posts 6 adjacent the lower portion thereof and having its axis disposed in a plane parallel with the axis of the shaft bearings 10.

Bevel gears 12 are meshed with smaller beveled gears 14 fixed to a transverse shaft 15 journaled at its respective ends in suitable self-aligning bearings 15a and as shown supported on a pair of pedestals 16. Shaft 15, as shown, is provided with a large central sprocket 17 which is driven by a roller chain 18 from a relatively small sprocket 19 which is shown as affixed to the armature shaft of a motor M. The gear ratios between the driving sprockets and beveled gears are of such relation to the windings of the screw conveyors formed on shafts 8 that bags or other articles delivered to the receiving end of the shafts 8 will be progressed steadily and comparatively rapidly. Each of the shafts 8 is directly driven from its left hand end by a chain 20 which is trained about a sprocket 21 on the outer end of the related stub shaft 12a and about a sprocket 22 fixed to the outer end of the appropriate shaft 8.

A pair of spaced horizontal guide rails 24 having smooth, rectilinear, opposed faces are suitably supported by angle irons 6b which extend inwardly and then upwardly from the upper ends of the two series of posts 6 and are spaced apart the appropriate distance and mounted at the proper height for effectively guiding the filled bags B in their travel through my apparatus. These guides 24 as shown extend throughout the greater part of the length of the machine. The guide 24 on the forward side of the machine (Figs. 1 and 2) extends parallel with the conveyor shafts 8a from the receiving end of the machine to a point within a few feet from the driving transmission M and then has a section 24a angled obliquely with reference to the main section 24 for directing the bags laterally outwardly of the machine. The opposite or rear side guide 24 terminates a foot or so short of the connection of the angled deflecting guide section 24a leaving a lateral opening in the rear guarding wall to permit discharging of the bags automatically and laterally of the machine, the lateral discharge causing the bags to fall or tilt to substantially horizontal position in leaving the supporting conveying shafts.

Directly below the right hand portion of the double screw conveyor formed by shafts 8 with the helical windings 8a therein, is mounted an elongated narrow horizontal coating trough 27 containing coating material such as melted wax and as shown supplied with the wax or other coating material from a heated supply tank 28 mounted at the right hand end of the machine and having a supply connection or conduit 29 provided with a shutoff valve 29a adjacent the tank. In the bottom of the tank, as shown, I provide a U-shaped coil or steam pipe 30, the ends of which extend through the right hand end of the wax trough and are sealed therewith and connected to a suitable source and return pipe of a steam line. Trough 27, as shown, extends from a point adjacent the right hand end of the machine throughout slightly greater than half the length of the shafts 8, the forward end of the trough, as shown, being inclined.

As illustrated, my apparatus provides a means for intermittently delivering filled bags to the

right hand end of the machine and for tilting such bags during the delivery to inverted position to properly dispose the same upon the supporting and conveying shafts 8 with the secured filling end thereof positioned between the shafts 8 and depending therebelow into the upper level of the melted wax or coating liquid within the tank 27. The delivery mechanism illustrated comprises an inclined elevator or booster 32 of endless conveyor type driven at its upper or delivery end by suitable means such as a chain driving connection 33 which may be trained about a suitable sprocket driven by chain or other connection 34 from a sprocket 35 fixed to the right hand end of one of the rotary shafts 8. The delivered bags are guided downwardly into vertical position centrally of the two shafts 8a by opposed downwardly converging centering plates 36 and 37 respectively.

Operation

The particular type of multi-wall paper bag illustrated in Fig. 5 of the drawings comprises, before being filled, a multiple tubular construction pleated and folded flatwise along longitudinal edges throughout the several plies of the material. The bottom edges of the bag are secured together by the manufacturer by folding a strip 40 of heavy reinforcing flexible material and this strip is lock-stitched at 41 in folded form through the upper and free edges thereof or through the several layers of paper constituting the tubular portion of the bag. In the manufacturing of the bag, the reinforced and stitched lower edge is usually sealed and protectively coated by the manufacturer with wax or other suitable air hardening coating material.

The bag B is, of course, distended and suitably held for filling with the upper or filling end open and granular or pulverized material is dispensed therein by a suitable dispensing machine, not shown, the bag being filled to a point somewhat below the upper end thereof. The filled bags then have their upper ends collapsed together in the manner of the lower ends previously described and a strip of reinforcing paper or material 40 is folded over the free edges of the filled end of the bag and stitched therethrough in the manner previously described. The bag so filled, with the upper filling end secured and reinforced, is ready for processing by my improved apparatus.

The filled bags with the filling ends secured and reenforced as previously described are disposed upon the endless conveyor or booster 32 automatically or manually, as the case may be, with the upper end of the bag disposed forwardly or upwardly with respect to the conveyor and the bag positioned longitudinally of the conveying belt. These bags are successively carried to the upper and delivery end of the conveyor 32 and are dropped therefrom on to the right hand end of Fig. 1 of the conveyor shafts 8 guided and centered by the cooperating converging centering plates 36 and 37. The bags in dropping from the elevator 32 are tilted and inverted, the normally upper ends thereof which have just been closed and stitched, being positioned downwardly with the wide tab disposed between the shafts 8 and depending therebelow into the melted wax trough 27. The bags are guided by the spaced screw conveyor shafts 8 in cooperation with the guide railings 24 and shafts 8 being rotated in opposite directions for conveying purposes. The bags are progressed or moved longitudinally through the machine with the depending tabs 43 dipping into the wax in the trough 27.

It will be noted that the wax level L of the trough 27 is naturally disposed horizontally and at a slight acute angle to the slightly upwardly inclined conveyor shafts 8 whereby the tabs will clear, or substantially clear, the left hand end of the trough as the bags pass over that end in movement through my machine. Thereafter further movement or travel of the bags from the forward end of the trough to the delivery end of the screw conveyor shafts 8 affords adequate time for the wax or other coating material to dry and harden before the bags are delivered. As the bags move to the delivery end of the machine the angled guide section 24a causes lateral delivery of the bags from the rear side of the machine and the bags in discharge will fall horizontally.

Throughout this operation it will be noted that the rotary shafts 8 with the conveyor coils 8a secured thereto serve both the function of constituting the support for the inverted upright filled bags as well as the mechanism for moving the bags longitudinally through the machine. The rounded or rod construction of the conveyor coils prevent any cutting or injury to the bags in the conveyor action. The gear ratios of the transmission mechanism, including the motor sprocket 19, large sprocket 17, bevel gears 14 with meshed bevel gears 12 and the relation thereof to the pitch of the conveyor convolutions, are proportioned and related to cause the bags to be progressed in close spaced relation as fast as they are delivered by the elevator 32. Thus the machine has a high capacity for work and requires no manual labor in so far as the tilting of the bags, disposal of the same in upwardly inverted position on the shafts 8a, progression of the bags through the machine and coating of the depending tabs, as well as drying, are concerned.

From the foregoing description it will be seen that I have provided a simple, comparatively inexpensive and highly efficient apparatus, capable of production at low cost, and which is fully automatic and continuous in operation for successively coating the secured filling ends of flexible containers, such as paper bags and the like.

It will further be seen that I have provided a simple, inexpensive and highly efficient method for successively coating by continuous operation a multiplicity of flexible bag ends after the bags have been filled and the filling ends secured.

My method will be apparent from the foregoing description relating to operation and structure of my apparatus and consists generally in first inverting a filled bag having the filling end collapsed and secured to form a tab and thereafter moving the inverted bag through a substantially horizontal course while immersing the lower tab or secured edges of the bag in self-hardening coating, material such as wax, throughout at least a portion of the traveling movement of the bag. Additional steps of my method include preferably the further movement of the bag throughout the predetermined course after the depending secured edge or tab thereof has passed from the coating material to allow the coating material to harden. More specifically my method includes the receiving, supporting and conveying of the inverted filled and secured bags through a combination support and conveying medium which also has guiding functions in assisting and maintaining the bags as they are processed in upright position.

It will, of course, be understood that various changes may be made in the apparatus and that

specific details of the steps and variances in the sequences thereof may be made all within the scope of my method invention.

What is claimed is:

1. Apparatus for coating and sealing the secured and collapsed filling end of a filled paper bag or the like having in combination, a combination supporting and conveyor medium disposed substantially horizontally for receiving the closed and secured filling end of a filled bag, said medium having a central longitudinal slot extending throughout the greater part of its length for accommodating the projecting secured extremity of said bag and having opposed, cooperating elements adapted to only frictionally engage the opposite sides of the filled bags, and a trough mounted directly below said conveyor for containing coating material at a level to cover said projecting portion of the closed end of said bag and coat the same during a part of the travel of said bag on said conveyor, said conveyor extending for some distance beyond said trough to allow the coated portion of said bags to dry and means at one end of said conveyor for facilitating removal of the processed bags therefrom.

2. Apparatus for coating and sealing the secured and collapsed filling end of a filled paper bag or the like having in combination, a pair of spaced elongated screw conveying and supporting shafts disposed in substantially a horizontal path, the convolutions of the screw elements of said shafts being spaced much closer than the width of said filled bag, means for driving the same, guiding means disposed above said shaft and substantially horizontally disposed for engaging and guiding the vertical sides of bags to be processed, said shafts being positioned for receiving an inverted filled bag having its filling end collapsed and secured to form a downwardly projecting tab, said shafts being of a diameter to at least partially support said bags with the tabs depending downwardly at one side of said shafts, and a trough mounted directly below said shafts and containing coating material at a level to cover said projecting tab and coat the same during a part of the travel of said bags along said conveying shafts.

3. Apparatus for coating and sealing the secured and collapsed filling end of a filled paper bag or the like having in combination, a pair of spaced parallel screw conveying shafts disposed in substantially horizontal relationship for successively receiving at one end of said apparatus a series of inverted filled paper bags or the like with the filling ends thereof collapsed and secured together to form depending tabs accommodated in the space between said parallel shafts, the screw elements of said conveying shaft having their convolutions spaced much closer together than the widths of said filled bags to only engage frictionally, opposite side portions of said bags, means for driving said screw conveyor shafts in opposite directions to progress said bags, and a trough mounted below said shafts and containing coating material at a level to cover said projecting tabs during a part of the travel of said bags along said conveyor shafts.

4. The structure set forth in claim 3, wherein said trough is mounted horizontally and said shafts are inclined from the horizontal slightly upwardly from their receiving ends toward their delivery ends whereby said tabs after coating with material will substantially clear the farther end of said trough.

5. The structure set forth in claim 3, and said shafts extending considerably beyond said trough for drying the coating material before delivery of said bags and means associated with the outer ends of said shafts for automatically discharging said coated bags laterally of said apparatus.

6. Apparatus for coating and sealing the secured, projecting and collapsed filling ends of filled paper bags or the like, having in combination a combination supporting and conveying medium, comprising a pair of parallel substantially horizontal conveyor elements adapted to engage opposite sides of the bottom portion of inverted bags and spaced apart to provide an elongated slot for accommodating the projecting ends of said bags, means for driving said medium and a trough mounted below said parallel conveyor elements and extending longitudinally thereof and containing coating material at a level to cover said projecting ends during part of the travel of said bags upon said conveyor elements.

7. Apparatus for coating and sealing the secured, projecting and collapsed filling ends of filled paper bags or the like, having in combination a combination supporting and conveying medium, comprising a pair of parallel substantially horizontal conveyor elements adapted to engage opposite sides of the bottom portion of inverted bags and spaced apart to provide an elongated slot for accommodating the projecting ends of said bags, means for successively delivering a series of bags to the receiving end of said supporting and conveyor medium and for tilting

said bags through approximately 90° and for directing said bags to be successively supported in inverted, upright position upon said medium and means below said medium for coating the projecting secured portions of said bags during travel thereof upon said conveyor elements.

8. Apparatus for coating and sealing the secured, projecting and collapsed filling ends of filled paper bags or the like, having in combination a combination supporting and conveying medium, comprising a pair of parallel substantially horizontal conveyor elements adapted to engage opposite sides of the bottom portion of inverted bags and spaced apart to provide an elongated slot for accommodating the projecting ends of said bags, a cross conveyor having its delivery end disposed at some height above the receiving end of said medium and adapted to deliver filled bags substantially horizontally and to tilt said bags into inverted, upright position during such delivery, and a trough mounted below said parallel conveyor elements and containing coating material at a level to cover said projecting ends during a part of the travel of said bags upon said conveyor elements.

9. The structure set forth in claim 8, and converging, centering and guiding means between the delivery end of said cross conveyor and said medium, for assisting in precisely positioning said filled bags upon said medium in proper vertical, inverted position.

EDWIN F. ANDERSON.
